GUSTAV SCHLATTER, OF STEINACH, AND GUSTAV SEGIN, OF ARBON, SWITZERLAND,
ASSIGNORS TO FIRMA ADOLPH SAURER, OF ARBON, SWITZERLAND, A FIRM ORGAN-
IZED UNDER THE LAWS OF SWITZERLAND.

REGULATING DEVICE FOR WATERING-CARTS.

1,349,440.

Specification of Letters Patent. Patented Aug. 10, 1920.

Original application filed April 13, 1917, Serial No. 161,875. Divided and this application filed March 27, 1919. Serial No. 285,668.

To all whom it may concern:

Be it known that we, GUSTAV SCHLATTER, residing at Steinach, Switzerland, Villa Ceranique, Rorschacherstrasse 1, and GUSTAV SEGIN, residing at Arbon, Switzerland, Rebenstrasse 41, have invented new and useful Improvements in Regulating Devices for Watering-Carts, of which the following is a specification.

10 Our invention relates to a regulating device for watering carts, which comprises a regulating valve mounted to turn and to move lengthwise in the spraying head and operated by the pressure of water, and a 15 hand operated control piston which brings about the longitudinal movement of the regulating valve controlling the length of the spray. The width of the spray is set by turning the regulating valve, and this 20 turning movement also is brought about by the pressure of water. To that end we provide another hand operated device which turns the regulating valve by means of a 25 rotary valve being arranged in the casing of the regulating valve coaxially with the same.

Our present application is a division of another application for Letters Patent filed by us in the United States Patent Office on 30 April 13, 1917, Serial No. 161,875, on which Letters Patent No. 1,302,227 were issued to us on April 29, 1919.

A regulating device according to our invention is illustrated by way of example in 35 the accompanying drawing.

Figure 1 is a longitudinal section of the device;

Fig. 2 is a section on line C—D of Fig. 1;

Fig. 3 is a section on line G—H of Fig. 1

40 on an enlarged scale, and

Fig. 4 is a section on line E—F of Fig. 1.

In the spraying head 1 closed at both ends by covers 2 and 46, are mounted two pistons or valves, the regulating valve 4 and the control piston 5 which is fitted into the valve 4 and sliding with a water tight fit in the cover 2. Longitudinal movement of the regulating valve 4 determines the length of the spray, and its rotation the width of the 50 spray. The spraying head 1 is provided on the left side with a number of spraying holes 9. The control piston 5 is hollow and open at both ends. In the center it is provided, symmetrically of its longitudinal

axis, with two sets of slots 11, two recesses 55 12 and 13 and a groove 14 arranged in the center cooperating with slots and cylindrical guiding surfaces of the regulating valve 4, in which the control piston 5 is working.

By moving the control piston to the right 60 or to the left by means of the bell crank lever 41, 42, the regulating valve 4 is shifted lengthwise above the spraying holes 9, and the length of the spray is thus adjusted. Water passes through a breeches pipe 43 into 65 two casings 44 and 45 cast on the spraying head 1. From the casing 44 it reaches the spraying holes 9.

In the center of the cover 46, closing the spraying head 1 on the right, is cast a pipe 70 47. In the latter is mounted a tubular projection 48 of a rotary valve 49 which works to the right of the cover 46 in a separate chamber. The rotary valve 49 is so connected to the regulating valve 4 that the 75 latter is positively forced to rotate with it, but can move longitudinally independently of it. Any well known or approved expedient may be employed for this purpose, as for instance, a longitudinal rib on one of these 80 members, sliding in a mating longitudinal groove in the other member as hereinafter described. The chamber is closed by a cover 50. The cover 50 is provided with a chamber 51 communicating with the second water 85 supply pipe 45 through a conduit 52, and has an inner tubular projection 53 which adjoins a water outlet pipe 10 leading to an open reservoir of the cart. The rotary valve 49 has in its interior a second rotary valve 90 54 which fits tightly into it. The spindle 55 of the said valve 54 passes to the outside through the cover 50 and can be turned by hand by means of a lever 56.

The rotary valve 49 comprises an outer 95 casing 57, as shown in Fig. 3, and two diametrically opposite hollow blades 58 and 59 projecting beyond the casing. From the casing of the spraying head 1 start two diametrically opposite bridges 60 and 61 extending to the casing 57. These bridges and blades 58 and 59 form in the position illustrated four chambers *d e f g* of equal size.

Within the outer casing 57 the rotary valve 49 has an inner casing 62 in which is 105 mounted the second rotary valve 54. The latter has in cross section the shape of a cross, see Fig. 3. One arm 63 is provided

at each end with trough-shaped projections 64, 65 and 66, 67 respectively, and the other arm 68 has at each end a lug 69 and 70 respectively.

5 The casings 57 and 62 are connected together by a number of ribs, next to which in one or in both casings are arranged slots. The walls of the blades 58 and 59 are extended inward to the casing 62. Between 10 their ends connecting together the casings in the form of ribs, are arranged in the casing 62 slots 71 and 72. At both sides of the ribs are arranged further slots 73, 74, 75 and 76 in the casing 62, and slots 77, 78, 79 15 and 80 in the casing 57. Normally to the blades 58 and 59, between the casings 57 and 62, are provided ribs 81^a and 82^a, at both sides of which are arranged slots 82, 83, 84 and 85 in the casing 62.

20 In the illustrated position of the parts, water passes from the casing 45 through the conduit 52 and the chamber 51 of the cover 50 into the blades 58 and 59, from the latter through the slots 71 and 72, troughs 64 and 67, slots 73 and 75 and slots 77 and 79 25 into the chambers *d* and *f*. As the latter are closed by the fixed walls 60 and 61, the valve 49 will rotate clockwise owing to the pressure of the water on the blades 58, 59. 30 The water filling the chambers *e* and *g* escapes through the slots 80, 85 and 78, 83 into the interior of the rotary valve 54 and thence through the projection 53 into the pipe 10. The rotation of the valve 49 con- 35 tinues until the slots 71 and 72 have passed completely beyond the bridges between the troughs of the valve 54. From that moment no water can escape from the blades 58 and 59. Simultaneously with the closing of the 40 blades, the lugs 69 and 70 cover the slots 83 and 85, so that water in the chambers *e* and *g* is held back, and holds the valve 49. The regulating piston 4 coupled to 45 valve 49, has now closed a number of spraying holes, and therefore the width of spray is correspondingly reduced. If it is to be reduced still more, the valve 54 is turned again, whereupon the slots 71, 72 etc. are opened again. This can be repeated until 50 the blades 58 and 59 strike the partitions 60, 61. At that moment, the spray holes 9 situated within the reach of the regulating valve, are completely closed. In order to 55 open them again, the valve 54 is turned in the opposite direction, so that the slots 71 and 72 are brought into communication with the troughs 65 and 66, and the chambers *e* and *g* are filled with water, while water from the chambers *d* and *f* escapes through 60 the slots 77 and 79.

Rotation of the valve 49 is transmitted to the regulating valve 4 by a ring 86 mounted on the hub 48 and provided with two or more arms 87 and 88, see Fig. 4, which ter-

minate in teeth 89 and 90 and engage with 65 parallel guides 91 of the regulating valve 4, so that the latter has to take part in the rotation of the valve 49, while being able to move lengthwise.

In order to enable the valve 49 to be positively rotated in the event of its jamming or failing to respond to the water pressure, the rotary valve 54 is provided at its front end with teeth 92 which can engage with teeth 93 of the valve 49 if it should get jammed. 75 This insures the possibility of rotating the valve 49 under any circumstances, that is to say, of operating it manually, if it fails to respond to the water pressure.

What we claim is:

1. In a regulating device for watering carts, the combination with a regulating valve mounted to move lengthwise and to turn in the spraying head and operated by the water pressure, longitudinal movement 85 of the said valve determining the length of the spray and its rotation determining the width of the spray, of a hand operated control device effecting the longitudinal movement, and of another hand operated device 90 effecting the rotation of the regulating valve, a second valve rotated by the water pressure being arranged in the casing of the regulating valve coaxially with the same, and connected to it so as to allow the regulating valve to move longitudinally independently of the rotary valve, but to participate in its rotation.

2. In a regulating device for watering carts, the combination with a regulating 100 valve mounted to move lengthwise and to turn in the spraying head and operated by the water pressure, longitudinal movement of the said valve determining the length of the spray and its rotation determining 105 the width of the spray, of a hand operated control device effecting the longitudinal movement, and of another hand operated device effecting the rotation of the regulating piston, a second valve rotated by the 110 water pressure being arranged in the casing of the regulating valve coaxially with the same, said rotary valve comprising blades 115 working in chambers of the valve casing, separated by partitions, a hand operated rotary valve being mounted in the said rotary valve and adapted to open and close the conduits supplying water under pressure to the chambers of the casing and again carrying it away from same chambers.

In testimony whereof we have signed this specification in the presence of two subscribing witnesses.

GUSTAV SCHLATTER.
